UNITED STATES PATENT OFFICE.

JOHN C. SHEERAN, OF PITTSBURG, PENNSYLVANIA.

DESIGN FOR A CLOTHES-LINE HOLDER.

SPECIFICATION forming part of Design No. 31,185, dated July 11, 1899.

Application filed February 21, 1899. Serial No. 706,417. Term of patent 7 years.

To all whom it may concern:

Be it known that I, JOHN C. SHEERAN, a citizen of the United States of America, residing at Pittsburg, in the county of Allegheny and State of Pennsylvania, have invented and produced a new and original Design for a Clothes-Line Holder; and I do hereby declare the following to be a full, clear, and exact description thereof, reference being had to the accompanying drawings, which form a part of this specification.

The leading features of my design consist in the curved upper portion bent in the form of a loop, the outwardly-extending central portions, and the inwardly-projecting points or spikes, as shown in the drawings, in which the design is formed from a single piece of round wire or rod, the two extremities C of which are pointed and bent at a right angle in the form of spikes. At the center of the holder the wires are bent outwardly, as shown

at B on the drawings, and the upper portion A bent in the form of a loop and the said loop curved outwardly at the top and at the point of connection with the straight portions B to present a concaved surface. The two legs joined by the loop A are arranged parallel, the curves and bends of the one corresponding with the other.

Having described my invention, what I claim as new, and desire to secure by Letters Patent, is—

The design for a clothes-line holder substantially as shown and described.

In testimony whereof I have hereunto affixed my signature in the presence of two subscribing witnesses.

JOHN C. SHEERAN.
